(57) CLAIM

The ornamental design for the stylized shirt, as shown and described.

DESCRIPTION

The file of this patent contains at least one photograph executed in color. Copies of this patent with color photographs will be provided by the Office upon request and payment of the necessary fee.

FIG. 1 is a forward perspective view of a stylized shirt showing my design;

FIG. 2 is a back view thereof;

FIG. 3 is a right perspective view thereof;

FIG. 4 is a left view thereof; and,

FIG. 5 is a top perspective view thereof.

The stand upon which the stylized shirt is draped does not form part of the claimed design and is disclaimed, as is the hanger upon which the stylized shirt is hung. The stand and hanger show environmental structure.
